GLASS DIAL

Warren W. Loveland, La Crosse, Wis.

Application August 19, 1948, Serial No. 148,193

Term of patent 3½ years

(Cl. D52—1)

To all whom it may concern:

Be it known that I, Warren W. Loveland, a citizen of the United States, residing at the city of La Crosse, in the county of La Crosse and State of Wisconsin, have invented a new, original, and ornamental Design for a Glass Dial, of which the following is a specification, reference being had to the accompanying drawings, forming part thereof.

Fig. 1 is a plan view of the face of a glass dial, showing my new design.

Fig. 2 is a plan view of the reverse side thereof.

Fig. 3 is an edge view of the glass dial of Figs. 1 and 2.

Fig. 4 is an enlarged sectional view of the glass dial taken on the line 4—4 of Fig. 1.

I claim:

The ornamental design for a glass dial, as shown.

WARREN W. LOVELAND.
